(57) **CLAIM**

The ornamental design for a tire as shown and described.

DESCRIPTION

FIG. 1 is a perspective view of a tire, showing our new design;

FIG. 2 is a right side elevational view thereof, the left side elevational view being a mirror image thereof;

FIG. 3 is a front elevational view thereof, the rear elevational view being a mirror image thereof;

FIG. 4 is a cross-sectional view taken along line 4-4 of FIG. 2; and,

FIG. 5 is a detail view of a portion of the tire.

The broken lines shown in the figures are for the purpose of illustrating portions of the tire that form no part of the claimed design.
